METHOD OF AND APPARATUS FOR SETTING
FEEDING MECHANISMS FOR MATERIAL
WORKING MACHINESCarl Stackawicz, Arlington, N. J., assignor to
Western Electric Company, Incorporated, New
York, N. Y., a corporation of New York

Application February 14, 1948, Serial No. 8,464

9 Claims. (Cl. 164—89)

1

This invention relates to a method of and apparatus for setting feeding mechanisms for material working machines such as automatic punch presses, and has for its objects, a method of and apparatus for varying the material feeding means for such machines accurately with a minimum loss of time and no loss of material as required when practicing the conventional methods of setting feeding mechanisms of such machines.

The conventional automatic punch presses for punching and blanking parts from large coils or strip stock have feed rolls between which the stock is advanced longitudinally relative to the punches and blanking dies of the press. The distance the stock is fed during each operating cycle of the press must vary with variations in the size of parts to be blanked from the stock. Furthermore, in machines of this type, which are operable at variable speeds depending upon the size of the part to be blanked and/or the thickness of the material from which it is to be blanked, there may exist an overrunning of the feed rolls or other conditions to cause inaccurate advancement of the material for one or more blanking operations throughout the length of the stock.

In certain instances where both punching and blanking operations are performed to produce perforated parts blanked from the stock, although both perforating and blanking operations are performed simultaneously during an operating cycle of the press, they are in effect, performed successively on each part of the product from the stock. In other words, a portion of the stock from which a part is to be produced, is punched during one operating cycle and then advanced to the blanking die for the next operating cycle when the part is blanked from the stock. In such instances pilot pins are mounted on the blanking punch to enter the apertures in the stock formed during the previous punching or perforating operation to make a final adjustment in the stock, freed at that time from the feed rolls, to produce an accurate part. However, unless the stock is advanced the given distance required for that particular part, or within a minute variation therefrom, the pilot pins will fail to enter the apertures and will thus damage the part blanked from the stock.

Heretofore, the feeding mechanisms of such machines have been set by the cut and try method, the setup man, initially guessing at the adjustment of the eccentric connection between the feed roll actuating mechanism and the crank shaft of the press and then operating the press

2

while the feed rolls advance material to the dies. The operator then determines the conditions of the parts produced from the material, observing the positions of the apertures within the blanked parts to determine how far off one way or the other the initial setting of the feeding mechanism was made. The operator again adjusts the feeding mechanism attempting to correct the initial setting and again operates the machine, feeding material thereto. This method of setting up the press requires considerable time and material. It is not possible during this method to determine whether or not the press is set accurately for the selected material and the desired speed of the press unless numerous parts have been blanked from the material.

In accordance with the aforementioned objects, the invention comprises an apparatus by the aid of which the method may be practiced for setting the feeding mechanism of an automatic material working machine such as a punch press including feed rolls driven by an adjustable mechanism connected to the crank shaft of the machine, the apparatus including a marking element operated at a given time during each operating cycle of the machine to mark a material or member advanced by the feed rolls of the machine relative to a measuring means whereby the material feeding movements of the feed rolls may be accurately measured to determine whether or not the driving means for the feed rolls has been accurately set. A calibrated element for the adjusting mechanism of the driving means for the feed rolls may be actuated to correct any error in the initial setting of the machine.

More specifically, the apparatus includes a table over which a material or member may be advanced intermittently by the feed rolls of the machine. A vernier scale divided into tenths of an inch is positioned adjacent the path of the member and a pointer movable on a micrometer screw for successive alignment with the marks on the member carries a magnifying glass and a locating hairline to obtain accurate reading of the scale. The distance between the marks on the member caused by the marking element during each operating cycle of the machine may be calculated in thousandths of an inch by the combined readings of the vernier scale, and a micrometer on the micrometer screw. The standard adjusting means including an eccentric connection between the crank shaft of the machine and an actuating rod for intermittently driving the feed rolls includes an adjusting screw formerly

3

actuated by a wrench which has been replaced by a calibrated wheel movable relative to an arrow or pointer on the wheel by the aid of which additional adjustments may be made to increase or shorten the feeding stroke of the machine by rotating the calibrating wheel a given distance in either direction.

Other objects and advantages will be apparent from the following detailed description when considered in conjunction with the accompanying drawings, wherein

Fig. 1 is a fragmentary rear elevational view of an automatic machine such as a punch press illustrating the apparatus by the aid of which the method may be practiced;

Fig. 2 is a top plan view of the major portion of the apparatus;

Fig. 3 is a vertical sectional view taken along the line 3—3 of Fig. 2;

Fig. 4 is an enlarged vertical sectional view of the marking unit taken along the line 4—4 of Fig. 2;

Fig. 5 is a vertical sectional view taken along the line 5—5 of Fig. 2;

Fig. 6 is an enlarged fragmentary sectional view of a portion of the apparatus;

Fig. 7 is a fragmentary end elevational view of the adjusting mechanism for the feed rolls; and

Fig. 8 is a fragmentary sectional view taken along the line 8—8 of Fig. 7.

The machine employed to illustrate the invention is an automatic press indicated generally at 10 capable of receiving dies for perforating, punching, blanking and/or forming articles of strip or sheet material. The machine includes a main frame 11 including a base 12 supporting a mounting plate 14 for a lower die or group of dies 15. A reciprocable ram or upper member 16 is supported for vertical movement in the conventional manner upon guide rods 17, only one of which is shown in Fig. 1 of the drawing. The ram 16 is reciprocated through its operative connection with a crank shaft 18, on one end of which is mounted a head 20 for connection with the feed rolls 21 and 22 of the machine. The head 20 has an integral guide 23 to receive and guide the inner end of a spindle 24. The inner end of the spindle 24 is internally threaded to receive an adjusting screw 26 rotatably supported in the head 20 and held against longitudinal movement therein. The outer end 27 of the adjusting screw 26 is square in cross-section to receive an adjusting wheel 28 having calibrations 29 thereon to be moved relative to a pointer mounted at a suitable position on the periphery of the head 20.

Through rotation of the adjusting screw 26 the axis of the spindle 24 may be moved relative to the axis of the crank shaft 18 to vary the rotary movement imparted to the feed rolls 21 and 22 depending upon the distance the material is to be advanced relative to the dies in the machine during each operating cycle of the machine. A connecting element 30 having its upper end mounted on the spindle 24 has its lower end extending through a sleeve guide 31 and provided with rack-like teeth for operative connection with the conventional driving means for the drive roll 21 including the conventional roller friction clutch whereby the feed rolls will be driven in one direction during movement of the element 30 in one direction, that is, during one-half cycle of the crank shaft 18, the feed rolls being held against rotation during the other

75

4

half cycle of the crank shaft. It is not believed necessary to show the mechanism operatively connecting the element 30 with the feed rolls, nor is it believed necessary to show in detail the mechanism for raising the feed roll 22 free of the material during the period of each operating cycle when the dies or other material working tools of the machine are performing work on the material.

10 In machines of this type capable of automatic operation during variable revolutions per minute and wherein the material may be advanced varied distances during each operating cycle, and these distances differing within thousandths of an inch, the accuracy required in setting up the machine for producing a given part or article is of great importance. A small variation, one way or the other from an accurate setting of the machine would result in the machine producing useless parts or articles. On the other hand, the cost of manufacturing such parts or articles, not only depends upon how fast they may be produced from the machine, once it is accurately set up for operation, but upon the time spent and the material lost in setting up the machine.

15 The apparatus, by the aid of which the method may be practiced, for rapidly and accurately setting up machines for operation by adjusting the feeding means thereof to advance material predetermined distances, includes a table 35 having its left end (Fig. 2) nested in a recess 36 of an angular mounting bracket 37 and secured thereto by screws. A bracket 38 mounted on the main frame 11 of the machine is grooved at 39 to receive mounting bolts for mounting the apparatus to the machine. A scale 40 is mounted on the upper surface of the table 35 adjacent a path for material 41 advanced intermittently by the feed rolls 21 and 22 of the machine. The scale 40 is divided first into inches indicated by numerals 42 and then into tenths of inches by graduations 43.

20 A bracket 45 mounted on the table 35 and extending vertically therefrom carries a friction drag unit indicated generally at 46 and including a ball member 47 urged downwardly on the material 41 by a spring 48, the force of which may be varied by an adjusting screw 49 held in any adjusted position by a lock nut 50. The purpose of the unit 46 is to permit longitudinal movement of the material 41 by the feed rolls 21 and 22 and to hold the material against additional movement when the material is free during the portion of the operating cycle of the machine when the feed roll 22 has been moved upwardly from the material. The structure of the ball member 47 does not interfere with the initial sliding of the material 41 over the upper surface of the table 35 and between the feed rolls.

25 A micrometer screw 53 is mounted parallel with the scale 40, one end being journaled for rotation in the bracket 45, while the other end is mounted for rotation in a suitable bearing 54, the screw being held against longitudinal movement. The threads of the screw 53 are of such pitch that one thread equals one tenth of an inch to move a pointer or indicating element 55, threadedly mounted at 56 on the screw, one-tenth of an inch during each cycle of rotation of the screw. A micrometer element 58 mounted on the outer end of the screw has graduations 59 thereon in one thousandths of an inch reading from a zero position 60 relative to an indicating element 62. The screw

75

line 61 on a stationary member 62. The screw

is rotated through the aid of a hand crank 63 mounted on the outer end thereof adjacent the micrometer 58.

The pointer 55 carries a grooved block 65 (Figs. 2 and 6) to straddle the adjacent edge 66 of the table 35 to maintain accurate movement of the pointer relative to the scale 40 and the material 41 during rotation of the micrometer screw 53. An aperture 67 is formed in the pointer 55 which is oval in general contour and positioned to move over the graduations 43 and the numbers 52 of the scale 40 to obtain accurate readings as herein-after described. A wire of a given gage indicated at 68 is stretched across the aperture 67 parallel with the indications 43 and in alignment with the point or indicating edge 70 of the pointer 55. To assist in accurately reading the position of the wire 68 relative to the scale 40, a magnifying unit 72 is positioned above the pointer 55 and supported by a bracket 73 mounted on the threaded portion 56 of the pointer unit.

Means is provided to mark the material 41 subsequent to each advancement thereof by the feed rolls to accurately indicate the material feed of the machine for a given setting of the feeding mechanism. This means includes a marking element 75 having an edge 76 to engage the material 41 and form a mark thereon during each reciprocal movement of the element. The element 75 is mounted on a holder 77 supported for vertical movement in a bracket 78 and normally urged upwardly by a spring 79. The bracket 78 is mounted upon the table 35 and has a cutaway portion 80 at its lower end for movement of the material 41 therebeneath. A round headed screw 81 is mounted in the upper end of the holder 77 to be engaged by the adjacent end of a rocking lever 82 (Figs. 2 and 3). The lever 82 is pivotally supported at 83 and has its other end notched at 84 to straddle a pin 85. The pin 85 is mounted in a rod 86 connected to a core 87 of a solenoid 88. The lower end of the lever 82 as well as the rod 86 rests upon a cushion 89 mounted upon a lower support 90 of the apparatus. The solenoid is energized through an electrical circuit under the control of a microswitch 92 mounted on a bracket 93 supported by the main frame 11 of the machine.

A cam 95 mounted in a fixed position on the upper member 16 of the machine is movable therewith to engage a roller 96 of a switch arm 97 to move the switch arm about its pivot 98 to move a plunger 99 inwardly to close the normally open microswitch 92. The cam 95 is so positioned that the switch 92 will be closed after each successive advancement of the material 41 by the feed rolls 21 and 22 near the lower end of the operating stroke of the machine. The switch 92 is in a circuit connected with a supply line through a conductor cable 100. A socket 101 is included in the circuit leading from the switch 92, which is completed by a plug 102 removably connected to the socket, through a conductor cable 103 to the solenoid 88 as illustrated in Fig. 2. In this manner, the microswitch 92 and the cam 95 may be made permanent parts of machines to which the apparatus may be removably connected, the electrical connection being made between the switch and the solenoid 88 by connecting the plug 102 with the socket 101.

The table 35 supports channel members 105 with spaced threaded apertures 106 in the lower portion thereof to receive winged screws 107 for the location of adjustable stops 108 predetermined distances from the scale 40 depending upon the

width of the material 41. Elongate apertures 109 are formed in the guides 108 to receive the screws 107 and to allow for selected adjustment of the guides relative to their screws when the screws are mounted in any of the threaded apertures 106. The inner ends of the guides 108 have reduced under portions to provide guiding surfaces 110 for the material 41 and overhanging lips 111 to maintain the material on the table.

10 In practicing the method for setting up a machine for operation to form articles from a given stock material, the apparatus is attached to the machine by sliding the heads of mounting bolts 112, carried in spaced apertures of the bracket 37, in the groove 39 of the bracket 38 on the machine and securing the apparatus in place by tightening the mounting bolts. The upper surface of the table is positioned to support a material 41 selected to receive the marks 114 made thereon by the marking element 76. The test material 41 may be of any desired, inexpensive structure suitable for advancement between the feed rolls 21 and 22 during operation of the machine and to receive the marks 114 from the marking element. In this manner, the stock material from which the articles are to be produced during operation of the machine, need not be employed during the setting of the machine as was necessary with the former cut and try method.

30 The stops 108 are adjusted to guide the material 41 in a path adjacent the scale 40 as it is advanced between the feed rolls 21 and 22. The operator, knowing the speed at which the machine should operate and the linear feed required 35 for the stock material from which the articles are to be produced, makes an initial adjustment of the eccentric connection 24, namely spindle (Figs. 7 and 8) relative to the axis of the crank shaft 18 by rotating the adjusting screw 26 through the aid of the hand wheel 28. The machine is now 40 set in operation and runs through a given number of operating cycles to cause the feed rolls 21 and 22 to intermittently advance the test material 41. The cam 95 operates the switch 92 45 into closed position intermediate the advancements of the material to cause energization of the solenoid 88, pulling the core 87 upwardly to rock the lever 82 about its pivot, to force the marking element 75 against the force of its spring 49 50 downwardly, whereby the edge 76 of the element will form a mark 114 at a given position on the material 41. The guided path of the marking element 75 assures accurate positioning of the marks 114 on the material whereby the 55 exact distance the material is moved during each operating cycle of the machine may be accurately measured.

50 After a given number of operating cycles of the machine have been completed, the machine is stopped and the distances between the mark 114 are measured. These measurements are accomplished through the cooperation of the pointer 55, the scale 40 and the micrometer 58. The pointer 55 is moved to register with the mark 114 nearest the marking element 75, that is, at the farthest position to the right (Fig. 2). When in this position, the operator may note the reading adjacent the wire, or hairline 68, on the scale 40 and obtain a complete reading by adding thereto the reading of the micrometer 58, that is, the graduation 59 registering with the indicating line 61. This may be described as the first reading. The second reading may be determined in the same manner when the pointer 55 is moved 65 to register with the second mark 114 to the left

of the first mark by rotation of the micrometer screw 53. By subtracting the first reading from the second reading, the distance between the first and second mark will be known. The operator continues taking the readings of the scale 40 and the micrometer 59 at each mark 114 in succession until all of the readings have been made and the distances between the markings determined. In this manner, the operator may determine the average advancement of material by the feeding rolls as a result of the initial setting of the eccentric connection of their driving means with the crank shaft. As previously explained, the distances the material is fed or advanced during each cycle of operation of the machine by the said rolls, are not always identical owing to possible overrunning of the roller friction clutch in the driving mechanism for the rolls. This condition exists mainly when the speed of operation of the machine is increased and for this reason, several operations must be made to determine the average distance the material will be fed or advanced as a result of a given setting of the feeding mechanism. To exemplify this condition, the feeding mechanism may be set to accurately feed the material a given distance during operation of the machine at a given speed and by varying the speed of operation of the machine, there will be a decrease or increase in the overrunning of the feed rolls to change the linear feed of the material without making adjustments in the feeding mechanism.

Subsequent to making the mark 114 on the material resulting from the initial setting of the feeding mechanism and determining the average distances between the mark, the operator may readily determine the additional adjustment necessary in the feeding mechanism, through rotation of the adjusting screw 26, to complete the adjustment of the feeding mechanism for the linear feed desired. The calibrated wheel 28 has graduations representing thousandths of an inch, relating to the linear travel of the material, and if, for example, the material 41 has been advanced two thousandths of an inch too far resulting from the initial setting of the machine, the graduated wheel 28 may be turned relative to its pointer, the distance of two markings 29 on the wheel in a direction to reduce the distance of travel of the feed rolls that amount.

It is to be understood that the above described arrangements are simply illustrative of the application of the principles of the invention. Numerous other arrangements may be readily devised by those skilled in the art which will embody the principles of the invention and fall within the spirit and scope thereof.

What is claimed is:

1. The method of setting the feeding mechanism of a material working machine having a main shaft to be driven through operating cycles to cause operation of tools on a stock material to be fed to the tools by feed rolls of the feeding mechanism driven intermittently variable rotary distances by an operating mechanism interposed between the feed rolls and the main shaft including an adjustable eccentric connection with the main shaft, the method comprising initially setting the material feeding mechanism by adjusting the eccentric connection relative to the axis of the main shaft to a position presumed to cause the feed rolls to advance material a given distance during each operating cycle of the machine, operating the machine through a predetermined number of cycles causing the feed rolls

to advance a material intermittently, marking the advanced material at the end of each movement thereof, measuring the distances between the markings on the material to determine the difference between the average linear feed for each of said cycles and a required feed to produce a given article, and subsequently adjusting the eccentric connection to vary the rotary movement of the feed rolls to condition them to advance a stock material the required linear feed during each operating cycle of the machine.

2. The method of setting the feeding mechanism of a material working machine having a main shaft to be driven through operating cycles to cause operation of tools on a stock material to be fed to the tools by feed rolls of the feeding mechanism driven intermittently variable rotary distances by an operating mechanism interposed between the feed rolls and the main shaft including an adjustable eccentric connection with the main shaft, the method comprising initially setting the material feeding mechanism by adjusting the eccentric connection relative to the axis of the main shaft to a position presumed to cause the feed rolls to advance material a given distance during each operating cycle of the machine, operating the machine through a predetermined number of cycles causing the feed rolls to advance a material intermittently, marking the advanced material at the end of each movement thereof, measuring the distances between the markings on the material to determine the difference between the average linear feed for each of said cycles and a required feed to produce a given article, and subsequently adjusting the eccentric connection a measured distance to increase or decrease the rotary movement of the feed rolls to condition them to advance a stock material the required linear feed during each operating cycle of the machine.

3. An apparatus for setting the feeding mechanism of a material working machine having a main shaft to be driven through operating cycles to cause operation of tools on stock material to be fed to the tools by feed rolls of the feeding mechanism driven intermittently variable rotary distances by an operating mechanism interposed between the feed rolls and the main shaft including an adjustable eccentric connection with the main shaft, the apparatus comprising a table mounted with its upper surface to support a material advanced intermittently by the feed rolls, a marking element positioned over the path of the material, means actuatable by the machine at a given time during each operating cycle thereof to actuate the element to make a mark on the material, and means to measure the distances between the markings on the material to indicate the distance stock material would travel between the feed rolls resulting from an initial setting of the adjustable eccentric connection, whereby a predetermined subsequent adjustment of the eccentric connection may be made to cause the feed rolls to advance stock material a given distance during each operating cycle of the machine.

4. An apparatus for setting the feeding mechanism of a material working machine having a main shaft to be driven through operating cycles to cause operation of tools on stock material to be fed to the tools by feed rolls of the feeding mechanism driven intermittently variable rotary distances by an operating mechanism interposed between the feed rolls and the main shaft including an adjustable eccentric connection with the main shaft, the apparatus comprising a table mounted

with its upper surface to support a material advanced intermittently by the feed rolls, a marking element positioned over the path of the material, means actuatable by the machine at a given time during each operating cycle thereof to actuate the element to make a mark on the material, a scale mounted on the table adjacent the path of the material with indicia representing given fractions of an inch, and a pointer movable relative to the material and scale and having aligned portions, one to register successively with the marks made on the material by the marking element and the other to lie parallel with the indicia on the scale to indicate the distance stock material would travel between the feed rolls resulting from the initial setting of the adjustable eccentric connection, whereby a known subsequent adjustment of the eccentric connection may be made to cause the feed rolls to advance the stock material a given distance during each operating cycle of the machine.

5. An apparatus for setting the feeding mechanism of a material working machine having a main shaft to be driven through operating cycles to cause operation of tools on stock material to be fed to the tools by feed rolls of the feeding mechanism driven intermittently variable rotary distances by an operating mechanism interposed between the feed rolls and the main shaft including an adjustable eccentric connection with the main shaft, the apparatus comprising a table mounted with its upper surface to support a material advanced intermittently by the feed rolls, a marking element positioned over the path of the material, means actuatable by the machine at a given time during each operating cycle thereof to actuate the element to make a mark on the material, a unit supported by the table and cooperating therewith to hold the material against movement intermediate the longitudinal advancement thereof by the feed rolls, and means to measure the distances between the markings on the material to indicate the distance stock material would travel between the feed rolls resulting from an initial setting of the adjustable eccentric connection, whereby a predetermined subsequent adjustment of the eccentric connection may be made to cause the feed rolls to advance stock material a given distance during each operating cycle of the machine.

6. An apparatus for setting the feeding mechanism of a material working machine having a main shaft to be driven through operating cycles to cause operation of tools on stock material to be fed to the tools by feed rolls of the feeding mechanism driven intermittently variable rotary distances by an operating mechanism interposed between the feed rolls and the main shaft including an adjustable eccentric connection with the main shaft, the apparatus comprising a table mounted with its upper surface to support a material advanced intermittently by the feed rolls, a marking element positioned over the path of the material, means actuatable by the machine at a given time during each operating cycle thereof to actuate the element to make a mark on the material, a guide cooperating with the scale and adjustably supported by the table for location varied distances from the scale to guide materials of different widths in a given path adjacent the scale, and means to measure the distances between the markings on the material to indicate the distance stock material would travel between the feed rolls resulting from an initial setting of the adjustable eccentric connection, whereby a

7. An apparatus for setting the feeding mechanism of a material working machine having a main shaft to be driven through operating cycles to cause operation of tools on stock material to be fed to the tools by feed rolls of the feeding mechanism driven intermittently variable rotary distances by an operating mechanism interposed between the feed rolls and the main shaft including an adjustable eccentric connection with the main shaft, the apparatus comprising a table mounted with its upper surface to support a material advanced intermittently by the feed rolls, a marking element positioned over the path of the material, means actuatable by the machine at a given time during each operating cycle thereof to actuate the element to make a mark on the material, a scale mounted on the table adjacent the path of the material with indicia representing given fractions of an inch, a pointer movable relative to the material and scale and having aligned portions, one to register successively with the marks made on the material by the marking element and the other to lie parallel with the indicia on the scale to indicate the distance stock material would travel between the feed rolls resulting from the initial setting of the adjustable eccentric connection, whereby a known subsequent adjustment of the eccentric connection may be made to cause the feed rolls to advance the stock material a given distance during each operating cycle of the machine.

8. An apparatus for setting the feeding mechanism of a material working machine having a main shaft to be driven through operating cycles to cause operation of tools on stock material to be fed to the tools by feed rolls of the feeding mechanism driven intermittently variable rotary distances by an operating mechanism interposed between the feed rolls and the main shaft including an adjustable eccentric connection with the main shaft, the apparatus comprising a table mounted with its upper surface to support a material advanced intermittently by the feed rolls, a marking element positioned over the path of the material, means actuatable by the machine at a given time during each operating cycle thereof to actuate the element to make a mark on the material, a scale mounted on the table adjacent the path of the material with indicia representing given fractions of an inch, a pointer movable relative to the material and scale and having aligned portions, one to register successively with the marks made on the material by the marking element and the other to lie parallel with the indicia on the scale, a magnifying lens mounted to move with the pointer to facilitate accurate registration of the first portion of the pointer with the marks successively and accurate reading of the scale adjacent each mark.

9. An apparatus for setting the feeding mechanism of a material working machine having a main shaft to be driven through operating cycles to cause operation of tools on stock material to be fed to the tools by feed rolls of the feeding mechanism driven intermittently variable rotary distances by an operating mechanism interposed between the feed rolls and the main shaft including an adjustable eccentric connection with the main shaft, the apparatus comprising a table mounted with its upper surface to support a material advanced intermittently by the feed rolls, a marking element positioned over the path of the material, means actuatable by the machine at a given time during each operating cycle thereof to actuate the element to make a mark on the material, a scale mounted on the table adjacent the path of the material with indicia representing given fractions of an inch, a pointer movable relative to the material and scale and having aligned portions, one to register successively with the marks made on the material by the marking element and the other to lie parallel with the indicia on the scale, a micrometer screw extending through a threaded aperture of the pointer and having threads of a given pitch to move the pointer the distance between the indicia on the scale during a given rotary movement of the screw, a micrometer rotatable relative to a stationary indicating line to rotate the screw and having indicia thereon representing smaller fractions of an inch than the indicia on the scale and cooperating with the scale to indicate the distance stock material would travel between the feed rolls resulting from the initial setting of

11

the adjustable eccentric connection, whereby a known subsequent adjustment of the eccentric connection may be made to cause the feed rolls to advance the stock material a given distance during each operating cycle of the machine.

9. An apparatus for setting the feeding mechanism of a material working machine having a main shaft to be driven through operating cycles to cause operation of tools on stock material to be fed to the tools by feed rolls of the feeding mechanism driven intermittently variable rotary distances by an operating mechanism interposed between the feed rolls and the main shaft including an eccentric connection movable varied distances relative to the axis of the main shaft by an adjusting screw having threads of a given pitch whereby each rotation of the adjusting screw will cause a given variation in the drive of the feed rolls by given variations in the eccentric connection relative to the axis of the main shaft, the apparatus comprising a table mounted with its upper surface to support a material advanced

5 10 15 20

12

intermittently by the feed rolls, a marking element positioned over the path of the material, means actuatable by the machine at a given time during each operating cycle thereof to actuate the element to make a mark on the material, means to measure the distances between the markings on the material to indicate the distance stock material would travel between the feed rolls resulting from an initial setting of the adjustable eccentric connection, whereby a pre-determined subsequent adjustment of the eccentric connection may be made to cause the feed rolls to advance stock material a given distance during each operating cycle of the machine, and a wheel to rotate the adjusting screw calibrated correspondingly to the pitch of the threads of the screw to vary the feeding mechanism to vary the linear feed of the material given fractions of an inch by the feed rolls.
